CLAIM

The ornamental design for a display screen or portion thereof with animated graphical user interface, as shown and described.

DESCRIPTION

FIG. 1 is a first image in a sequence of a display screen or portion thereof with animated graphical user interface; FIG. 2 is a second image in the sequence of the display screen or portion thereof with animated graphical user interface;

FIG. 3 is a third image in the sequence of the display screen or portion thereof with animated graphical user interface; FIG. 4 is a fourth image in the sequence of the display screen or portion thereof with animated graphical user interface;

FIG. 5 is a fifth image in the sequence of the display screen or portion thereof with animated graphical user interface; FIG. 6 is a sixth image in the sequence of the display screen or portion thereof with animated graphical user interface;

FIG. 7 is a seventh in the sequence of the display screen or portion thereof with animated graphical user interface;

FIG. 8 is an eighth image in the sequence of the display screen or portion thereof with animated graphical user interface;

FIG. 9 is a ninth image in the sequence of the display screen or portion thereof with animated graphical user interface; FIG. 10 is a tenth image in the sequence of the display screen or portion thereof with animated graphical user interface;

FIG. 11 is an eleventh image in the sequence of the display screen or portion thereof with animated graphical user interface;

FIG. 12 is a twelfth image in the sequence of the display screen or portion thereof with animated graphical user interface;

FIG. 13 is a thirteenth image in the sequence of the display screen or portion thereof with animated graphical user interface;

FIG. 14 is a fourteenth image in the sequence of the display screen or portion thereof with animated graphical user interface;

(Continued)

FIG. 15 is a fifteenth image in the sequence of the display screen or portion thereof with animated graphical user interface;

FIG. 16 is a sixteenth image in the sequence of the display screen or portion thereof with animated graphical user interface;

FIG. 17 is a seventeenth image in the sequence of the display screen or portion thereof with animated graphical user interface;

FIG. 18 is an eighteenth image in the sequence of the display screen or portion thereof with animated graphical user interface;

FIG. 19 is a nineteenth image in the sequence of the display screen or portion thereof with animated graphical user interface;

FIG. 20 is a twentieth image in the sequence of the display screen or portion thereof with animated graphical user interface;

FIG. 21 is a twenty-first image in the sequence of the display screen or portion thereof with animated graphical user interface;

FIG. 22 is a twenty-second image in the sequence of the display screen or portion thereof with animated graphical user interface;

FIG. 23 is a twenty-third image in the sequence of the display screen or portion thereof with animated graphical user interface;

FIG. 24 is a twenty-fourth image in the sequence of the display screen or portion thereof with animated graphical user interface;

FIG. 25 is a twenty-fifth image in the sequence of the display screen or portion thereof with animated graphical user interface;

FIG. 26 a twenty-sixth image in the sequence of the display screen or portion thereof with animated graphical user interface;

FIG. 27 is a twenty-seventh image in the sequence of the display screen or portion thereof with animated graphical user interface;

FIG. 28 is a twenty-eighth image in the sequence of the display screen or portion thereof with animated graphical user interface;

FIG. 29 is a twenty-ninth image in the sequence of the display screen or portion thereof with animated graphical user interface; and,

FIG. 30 is a thirtieth image in the sequence of the display screen or portion thereof with animated graphical user interface.

The appearance of the animated graphical user interface transitions between the images shown in FIGS. 1-30, The process or period in which one image transitions to another image forms no part of the claimed design.

The broken lines shown at the perimeter of each drawing figure illustrate a display screen or portion thereof that forms no part of the claimed design.

The “amazon” logo and abbreviated “a” logo forming part of the claimed design are registered trademarks of Amazon, Inc.
